FORK OR THE LIKE FLATWARE

David B. Hoover, 14 Ridgeland Road, Wallingford, Conn.

Filed Mar. 4, 1965, Ser. No. 84,092

Term of patent 14 years

(Cl. D54—12)

I claim:

The ornamental design for a fork or the like flatware, substantially as shown and described.
